[57] CLAIM

The ornamental design for an automatic teller machine, substantially as shown and described.

DESCRIPTION

FIG. 1 is a top, front, left side perspective view of an automatic teller machine showing my new design;

FIG. 2 is a top, rear, right side perspective view thereof;

FIG. 3 is a front elevational view thereof;

FIG. 4 is a left side elevational view thereof;

FIG. 5 is a top plan view thereof; and

FIG. 6 is a rear elevational view thereof.

The bottom of applicant's design is substantially plain and unadorned.

FIG. 1

FIG. 2

FIG. 3

FIG. 4

FIG. 5

FIG. 6
